DESIGN FOR A SLIDING BLADE KNIFE

Garfield L. Beckstrom, Chicago, Ill., assignor to
Autopoint Company, Chicago, Ill., a corpora-
tion of Illinois

Application December 26, 1947, Serial No. 143,363

Term of patent 14 years

(Cl. D22—3)

To all whom it may concern:

Be it known that I, Garfield L. Beckstrom, a citizen of the United States, residing at Chicago, in the county of Cook and State of Illinois, have invented a new, original, and ornamental Design for Sliding Blade Knife, of which the following is a specification, reference being had to the accompanying drawing, forming a part thereof.

In the drawing:

Figure 1 is a top plan view of a sliding blade knife embodying my new design, the blade being shown in dotted outline and in open position;

Fig. 2 is a view in side elevation of the same;

Fig. 3 is a top plan view of the knife with the blade closed;

Fig. 4 is a view in side elevation of the knife with the blade closed;

Fig. 5 is a view in rear elevation of the knife; and

Fig. 6 is a view in front elevation thereof.
The essential features of my design reside in those portions shown in full lines.

I claim:

The ornamental design for a sliding blade knife, substantially as shown and described.
